SOAP BUILDER OF REDUCED ALKALINITY

Walter C. Preston, Cincinnati, Ohio, assignor to
 The Procter & Gamble Company, Cincinnati,
 Ohio, a corporation of Ohio

No Drawing. Application May 8, 1935,
 Serial No. 20,423

9 Claims. (Cl. 87—5)

This invention relates to an efficient soap builder having alkalinity not substantially greater than that of soap solutions, consisting of a salt or salts of pyrophosphoric acid.

5 The word "builder" is used herein with the meaning given in Webster's "New International Dictionary of the English Language", second edition, 1935: "A substance, as soda ash, caustic soda, or sodium silicate, used with or in soap, to aid 10 in cleansing". Most soap builders improve not only the cleansing power but also the sudsing power of soap, both in soft water and in hard water, and in addition they are capable of softening hard water.

15 The builders commonly used in laundry soaps, such as sodium carbonate, sodium silicate, and trisodium phosphate, are stronger in alkalinity than soap itself when measured at the usual concentrations and temperatures of soap usage.

20 They owe their effectiveness as builders partly to their ability to combine with the constituents present in natural hard water and form precipitates with them, thus avoiding the loss of a certain amount of soap which would otherwise be 25 used up in precipitating these same constituents. It should be borne in mind that, in general, ordinary soap will not produce a noticeable lather or exert useful detergent effects in hard water until the hardness (or soap-precipitating) constituents of same have first been precipitated or 30 neutralized in some way.

35 The alkalinity of soap itself when dissolved in water has been reported by various observers to be about 9 to 10 on the pH scale. Ordinary soap builders, however, when added to soap in sufficient quantities to be effective as soap builders, unavoidably raise the alkalinity to a point which causes such undesirable effects as irritation of the skin, injury to woolens and other delicate fibers, deterioration of colors, etc.

40 I have found that a very effective soap builder, which can be readily adjusted in alkalinity so that it is mild in its action on the skin, on fabrics, dyes, etc., without losing its great efficiency as an aid in cleansing, can be prepared from tetra- 45 sodium pyrophosphate.

45 Tetrasodium pyrophosphate by itself has already been suggested as a soap builder, but it has an alkalinity in dilute solution nearly as great as that of sodium carbonate. However, by treating the tetrasodium pyrophosphate with suitable small quantities of an acid such as sulfuric acid, hydrochloric acid, phosphoric acid, pyrophosphoric acid, acetic acid, higher fatty acids such as lauric and oleic, etc., or with acid salts such

as sodium hydrogen sulfate, sodium dihydrogen phosphate, disodium dihydrogen pyrophosphate ($Na_2H_2P_2O_7$), and similar acid reacting materials, the normal tetrasodium pyrophosphate may be transformed in part into an alkali metal-hydrogen salt, and the alkalinity of the tetrasodium pyrophosphate can thus be reduced and adjusted within a wide range. For use as a soap builder, however, the alkalinity should not be reduced substantially below that of soap itself 10 under similar conditions such as concentrations of 0.5 per cent and at room temperature. My discovery is that when the alkalinity of the tetrasodium pyrophosphate is thus reduced to any point between that of the original salt and that of 15 a soap as measured in the usual concentrations of use, such as 0.5 per cent, the efficiency of the soap builder remains practically unimpaired, while its alkalinity and effect on the skin, etc., can be adjusted to any desired degree. Hence, my 20 builder can be used in any desired proportions so as to make soaps suitable for use in any kind of service, while the alkalinity can be regulated so that the soap will be mild in its action on the 25 hands, fabrics and colors. This, therefore, enables adjustment by the soap maker of his formulas to meet the requirements of various cleansing processes and for varying degrees of water hardness such as occur in different sections of the country.

30 This property of my pyrophosphate builder, of retaining its efficiency as a soap builder practically undiminished when its alkalinity is reduced even as low as that of soap by the means indicated, is peculiar to this substance alone, as far 35 as I am aware. If one attempts to reduce the alkalinity of other common soap builders such as sodium carbonate, sodium silicate, or trisodium phosphate, for example, in a similar way, their efficiency as soap builders is markedly decreased. 40

45 My builder softens water in a manner quite different from sodium carbonate, orthophosphate, silicate and similar water softeners, which form precipitates with the lime and magnesium, etc., in the water. The reaction of pyrophosphate salts with the calcium, magnesium, iron and other mineral salts present in hard water, in the presence of a suitable excess of the pyrophosphate, is thought to proceed as represented by the following chemical equations:

and

The calcium (also magnesium, iron, etc.) behaves as though it were sequestered in a complex ion, (CaP_2O_7) , and the concentration of free calcium (magnesium, etc.) ions in the solution is thus negligible when a sufficiently large excess of pyrophosphate is present. Thus, the calcium, magnesium, iron, etc., remain in solution, but in a form not precipitable by soap when sufficient pyrophosphate is present, and water softening is nevertheless complete, the process not being accompanied by any precipitation.

Other alkali metal pyrophosphate salts such as the potassium salt can be used in place of the sodium salts, but throughout this specification the sodium salt will be spoken of as representative of all.

While any of the means previously mentioned may be used to reduce the alkalinity of tetrasodium pyrophosphate in the practice of my invention, I find that one of the most convenient is to add to the normal $Na_4P_2O_7$ some $Na_2H_2P_2O_7$, or any alkali metal-hydrogen salt of pyrophosphoric acid of the general formula $M_xH_4-xP_2O_7$, where M is an alkali metal and x is any positive numerical value less than 4.

Solutions of $Na_2H_2P_2O_7$ are sufficiently acid to turn methyl orange indicator pink, while solutions of $Na_4P_2O_7$ are alkaline to phenolphthalein as well as methyl orange and have a pH value slightly less than that of Na_2CO_3 . By mixing these two salts of pyrophosphoric acid in the proper proportions, any degree of alkalinity or pH value lying between these two extremes can be obtained.

In preparing suitable mixtures of these salts, or in reducing the alkalinity of $Na_4P_2O_7$ by any other means, it is undesirable to reduce the alkalinity appreciably below the alkalinity of soap itself, and for the purpose of controlling such mixtures various means may be used. The determination of the pH of soap solutions is rather difficult and subject to considerable error; hence, this is not an easily carried out procedure. For practical purposes, however, indicators may be used to test solutions which have been prepared with the desired concentration and these will indicate with sufficient accuracy by the color whether the solution of builder is more or less alkaline than the solution of soap. Another method consists in adding the mixture of pyrophosphate salts to a soap solution and observing whether an increased cloudiness results, or not. Any increased cloudiness in solutions having the concentrations of soap and builder as ordinarily used in laundering would indicate too low a degree of alkalinity of the pyrophosphate salt mixture.

My invention, as previously explained, is not limited to pyrophosphate builders of an alkalinity equal to that of soap. It includes also any pyrophosphate builders of an alkalinity less than that of tetrasodium pyrophosphate, but not substantially less than that of soap. The exact degree of alkalinity that can be tolerated in the builder is dependent upon the use to which the built product is to be put. In general, mixtures containing more than one part by weight of $Na_2H_2P_2O_7$ to four parts by weight of $Na_4P_2O_7$ in solution have too low a pH value to come within the scope of my invention, while mixtures containing less than one part of $Na_2H_2P_2O_7$ to four parts of $Na_4P_2O_7$ come within its scope. It will be noted, therefore, that mixtures containing $Na_2H_2P_2O_7$ and $Na_4P_2O_7$ in the proportion of 1 to 4 by weight will have the following ap-

proximate apparent formula: $Na_{3.54}H_{0.46}P_2O_7$. Thus, in general, the mixtures coming within the scope of my invention have an average general formula of $M_xH_4-xP_2O_7$ where M represents an alkali metal and x is any value less than 4 but not less than about 3.54.

In the majority of cases, I prefer to use from 90 per cent to 95 per cent $Na_4P_2O_7$ and from 5 per cent to 10 per cent $Na_2H_2P_2O_7$, such mixtures being most widely applicable. The approximate apparent formulas for the 90-10 and 95-5 mixtures are $Na_{3.77}H_{0.23}P_2O_7$ and $Na_{3.88}H_{0.12}P_2O_7$, respectively.

As an example of my invention, I mix nine parts of $Na_4P_2O_7$ with one part of $Na_2H_2P_2O_7$. I then add two parts of this mixture to eight parts of powdered soda soap made from beef tallow. The resulting built soap is of a mildness similar to that of unbuilt tallow soap and affects indicators in a similar manner. When, under practical washing conditions, the built soap was compared with the unbuilt soap at 130° F. in equal concentrations in water of seven grains hardness per U. S. gallon, it was found that the built soap equaled the unbuilt tallow soap in sudsing power and excelled it in the removal of an oily type of soil from cloth. It will thus be seen that the builder replaced its own weight of soap as measured by sudsing power and more than its own weight of soap as measured by detergent power. When the comparison was made between built and unbuilt soap solutions having equal real soap concentrations, then an improvement in both sudsing and detergency was noted.

Other soaps than tallow soap, for example, coconut oil soap, palm kernel oil soap, palm oil soap and various mixtures of same may be improved in both sudsing and detergent power by the addition of my builder. Likewise, other alkali metal soaps such as the potassium soaps may be similarly improved, in which case, it may be advantageous to use the corresponding alkali metal pyrophosphate salts as builder.

My invention is not limited, however, to any particular method of mixing the pyrophosphate salts with the soap. Pyrophosphate salts of reduced alkalinity may be incorporated into soap in any of the forms in which soap is manufactured, as milled or unmilled bars, as flakes, powder, gel, or solution. It may be mechanically mixed in, as in the above example; it may be crutched into the molten soap; it may be dissolved in a soap gel or solution. In certain methods involving saponification in the crutcher, it is feasible to conduct the saponification with a mixture of tetrasodium pyrophosphate and caustic alkali, the alkalinity of the pyrophosphate salt being reduced to the desired point by the addition of fatty acid toward the end of the reaction.

While such a ready-for-use mixture may be manufactured and is for many purposes preferable, it also lies within the scope of my invention to add my builder to water prior to adding soap, or vice versa, or to add both builder and soap simultaneously but separately to the water. My invention resides in the presence in the detergent solution at the time of use, of soap and my soap builder of adjusted alkalinity, irrespective of the previous history of the builder. It is immaterial to the practice of my invention whether the alkalinity of my builder be reduced prior to or simultaneously with mixing with soap, or whether it be reduced prior to or simultaneously with solution in the wash water. My

builder may, however, be used in conjunction with other known soap builders if so desired.

Throughout the specification I have referred to the anhydrous pyrophosphate salts in the description of my invention. However, it is understood that I do not exclude from its scope those builders prepared from corresponding hydrated salts.

The word "soap" as used in this specification and claims means a water-soluble soap suitable for detergent purposes.

Having now described my invention, what I claim and desire to secure by Letters Patent is:

1. A soap builder having substantially the same alkalinity as soap alone under similar conditions of use, and adapted to improve the water softening, sudsing and detergent properties of water-soluble soap, comprising essentially an alkali metal pyrophosphate of reduced alkalinity having the general average formula

wherein M represents an alkali metal and x has a value less than 4 but not less than 3.54.

2. A soap builder suitable for improving the water softening, sudsing and detergent properties of soap, and suitable for use with soap in any proportion needed for varying cleansing requirements and for water of various degrees of hardness without increasing the alkalinity of the soap product beyond a predetermined low point, consisting of a tetra-alkali-metal pyrophosphate with an alkali-metal-hydrogen pyrophosphate, said mixture having the general average formula

wherein M represents an alkali metal and x has any value less than 4 but not less than about 3.54, the proportions of the two pyrophosphates being selected within this range so as to give the desired low alkalinity to the product.

3. A soap builder, efficient in water softening and in improving the sudsing and cleansing power of soap without substantially increasing the alkalinity of the soap, consisting essentially of a mixture of about 90 parts by weight of tetra-sodium pyrophosphate and about 10 parts by weight of disodium-dihydrogen pyrophosphate.

4. A soap builder, suitable for improving the water softening, sudsing, and detergent properties of water-soluble soap without increasing the alkalinity of the soap, which comprises a mixture of a tetra-alkali-metal pyrophosphate and an alkali-metal-hydrogen pyrophosphate, said mixture having substantially the same alkalinity as the soap and having the following general average formula

wherein M represents an alkali metal and x has

a value less than 4 but not less than about 3.54.

5. As a new washing composition, water-soluble soap and a builder for same consisting essentially of tetra-alkali-metal pyrophosphate and alkali-metal-hydrogen pyrophosphate in suitable proportion so that said builder has the general average formula

wherein M represents an alkali metal and x has any value less than 4 but not less than about 3.54.

6. As a new washing composition, water-soluble soap and a builder for same consisting of a mixture of about 90 parts by weight of tetra sodium pyrophosphate and about 10 parts by weight of disodium-dihydrogen pyrophosphate.

7. As a new washing composition, water-soluble soap and a builder for same consisting essentially of tetra-alkali-metal pyrophosphate and a sufficient proportion of a compound selected from the group consisting of acids and acid reacting salts such that said builder has the general average formula

wherein M represents an alkali-metal and x has any value less than 4 but not less than 3.54, the proportion of the ingredients in said builder being selected within this range so as to give the desired alkalinity to the product.

8. A built soap product having substantially the same alkalinity as the soap alone under similar conditions of use, containing as the essential ingredients water-soluble soap and an alkali-metal-pyrophosphate of reduced alkalinity having the general average formula

wherein M represents an alkali metal and x has a value less than 4 but not less than 3.54.

9. A soap builder suitable for improving the water softening, sudsing and detergent properties of water-soluble soap and suitable for use with water-soluble soap in any proportion needed for varying cleansing requirements and for water of various degrees of hardness without increasing the alkalinity of the soap product beyond a predetermined low point, comprising a mixture of tetra-alkali-metal pyrophosphate with a sufficient proportion of a compound selected from the group consisting of acids and acid reacting salts, to reduce the alkalinity of the said pyrophosphate so that it will have the general average formula

wherein M represents an alkali metal and x has any value less than 4 but not less than 3.54.
